CONTROL TRACK PICKUP

Joseph Lemon Underhill, Indianapolis, Ind., assignor to Radio Corporation of America, a corporation of Delaware

Application April 30, 1941, Serial No. 391,085

6 Claims. (Cl. 179—100.3)

This invention relates to control track pickups for picking up the impulses from a sprocket hole type control track in sound film apparatus.

The type of sprocket hole control track which may be used in this apparatus is described in the application of Charles M. Burrill, Serial No. 181,634, filed December 24, 1937, and in Dawson Patent No. 2,199,559. This control track may be used to control the turning on or off of loudspeakers as described in the application of Max C. Batsel, Serial No. 302,197, filed October 31, 1939 (RCV-6981) or it may be used to control the volume of sound reproduced or to otherwise control the amplifying or reproducing apparatus.

The foregoing applications disclose broadly the sprocket hole control track apparatus while the present application pertains to specific mechanism for the use of such control track film and the reproduction of the control track impulses in a commercial type of sound reproducer.

The apparatus of the present application is described as applied to a sound reproducer of the general type described and claimed in Loomis et al. Patent 2,019,147, issued October 29, 1935.

The invention involves a compact type of reproducer which is peculiarly adapted to the reproduction of the control track and which is so compact that it may be readily added to the soundhead without any material changes therein.

One object of the invention is to provide a pickup device for reproducing a sprocket hole control track.

Another object of the invention is to provide such a pickup device which may be installed in a commercial soundhead without requiring material modification thereof.

Another object of the invention is to provide such a pickup device which may be installed in a commercial type of soundhead without interfering with the normal operation thereof in the reproduction of sound from the sound record.

Another object of the invention is to provide such a pickup device which will pick up the impulses from the sprocket hole control track without being materially affected by irregularities in the lateral size or position of the sprocket holes.

Other and incidental objects of the invention will be apparent to those skilled in the art from a reading of the following specification and an inspection of the accompanying drawings in which

Figure 1 is a side view of a soundhead including my improved pickup device,

Figure 2 is an enlarged side view partly in section of the pickup device, and

Figure 3 is a vertical section through the pickup device.

Referring first to Fig. 1, the casing of the soundhead as described in the Loomis et al. patent referred to above is indicated at 10. The sound reproducing mechanism is supported on the plate 11 and includes an optical system 12 which directs the scanning beam of light through the film F on the drum 13. Light passed through the sound track of the film is directed through the prismatic lens 14 onto the photocell located in the housing 13. The film is drawn around the drum 13 by the constant speed sprocket 16 against which it is held by the pad roller 17.

In the normal operation of the soundhead the film would pass from between the sprocket 16 and the pad roller 17 to the hold-back sprocket 18 against which it is held by the idler 19 and, there being a free loop of film between the two sprockets the hold-back sprocket would prevent any jerks of the take-up reel from reaching the constant speed sprocket 16. In the present apparatus the loop between the sprockets 16 and 18 is enlarged sufficiently to permit the film to pass over the sprocket hole pickup. This sprocket hole pickup includes a film gate 20 which will be described in more detail herein-after, an exciter lamp 21 housed within the casing 22 and a photocell housed within the casing 23. The film F is held against the gate 21 by means of the roller 24 and the sprocket 18 which flex over a short span, as indicated in Fig. 1, so as to maintain it in contact with the aperture in the film gate.

Referring now to the details of the pickup construction as shown in Figs. 2 and 3: The roller 24 which feeds the film into the apparatus is preferably mounted on the common base member 32 which supports both the exciter lamp 21 and the photocell. The exciter lamp 21 is carried in a conventional type of sprocket 28 within the housing 22. The housing 22 is slotted at the bottom portion over the gate 20 to permit the passage of light therethrough and it may be provided with cooling fins 29 and with ventilating apertures 30.

After passing through the aperture in the film gate 20 the light passes through the sprocket hole control track or through the sprocket holes 55 between opaque portions of the track and enters

the photocell housing 23 through the aperture 27. The light thereby reaches the photocell 25 which is supported within the housing 23 by the usual socket 26.

The film gate 20 is peculiarly adapted to the present purpose particularly in the construction of the aperture 33 therein. This gate 20 is provided with a base 34 which is affixed to the base member 32 and which serves to support the gate perpendicularly to the said base member. The face of the gate is relieved so that the picture portion, the sound track portion and the control track portion of the film do not come in contact therewith.

The sprocket hole type of control track may be affected by differences in shaping of the sprocket holes in the positive film or by lateral weave of the film and any undesirable effect of these features upon the reproduction of the track is prevented by the construction of the gate. The aperture in the gate is so constructed as to sharply define the light beam laterally of the film and to restrict it to a space slightly narrower than the normal dimensions and positions of the sprocket holes. Longitudinally of the film it is not necessary or desirable to have the edges of the aperture so sharply defined and the apertures correspondingly constructed. In constructing the aperture I prefer to mill out a slot longitudinally of the gate and laterally of the film, as indicated at 35 in Fig. 3, and which aperture appears in transverse section in Fig. 2. This slot defines the aperture longitudinally of the film and at the same time it provides thin edges laterally of the film for defining the edges of the aperture in that direction. I then cut the aperture through from the opposite or outer side of the gate as indicated at 36 in Fig. 3 which sharply defines the longitudinal sides of the aperture. These longitudinal sides are spaced somewhat more closely together than the rounded ends of the sprocket holes and give correspondingly sharp definition of the track which is reproduced.

The film is pulled over the face of the gate 20 by the hold-back sprocket 18 as this control track does not require the regularity of motion of a conventional sound track. Due to the sprocket hole frequency the normal control frequency is 96 cycles per second and the normal errors in motion of the hold-back sprocket do not materially affect the reproduction of this frequency, while the dimensions of the reproduction aperture prevent the reproduction at any appreciable level of higher frequencies which may be incidental to either sprocket hole irregularities or irregularities in the motion of the sprocket 18.

I claim as my invention:

1. In combination with a soundhead including a photoelectric sound reproducer, a constant speed sprocket for pulling film past the sound

reproducer, and a hold back sprocket, a control track reproducer located between the constant speed sprocket and the hold back sprocket whereby the hold back sprocket pulls the film past the control track reproducer.

5 2. In combination with a soundhead including a photoelectric sound reproducer, a constant speed sprocket for pulling film past the sound reproducer, and a hold back sprocket, a photoelectric control track reproducer located between the constant speed sprocket and the hold back sprocket whereby the hold back sprocket pulls the film past the control track reproducer.

10 3. In combination with a soundhead including a photoelectric sound reproducer, a constant speed sprocket for pulling film over a rotatable drum past the sound reproducer, and a hold back sprocket, a control track reproducer located between the constant speed sprocket and the hold back sprocket whereby the hold back sprocket pulls the film past the control track reproducer.

15 4. In combination with a soundhead including a photoelectric sound reproducer, a constant speed sprocket for pulling film over a rotatable drum past the sound reproducer, and a hold back sprocket, a photoelectric control track reproducer located between the constant speed sprocket and the hold back sprocket whereby the hold back sprocket pulls the film past the control track reproducer.

20 5. In combination with a soundhead including a photoelectric sound reproducer, a constant speed sprocket for pulling film over a rotatable drum past the sound reproducer, and a hold back sprocket, a photoelectric control track reproducer located between the constant speed sprocket and the hold back sprocket whereby the hold back sprocket pulls the film past the control track reproducer.

25 30 6. In combination with a soundhead including a photoelectric sound reproducer, a constant speed sprocket for pulling film over a rotatable drum past the sound reproducer, and a hold back sprocket, a photoelectric control track reproducer located between the constant speed sprocket and the hold back sprocket whereby the hold back sprocket pulls the film past the control track reproducer, said control track reproducer comprising an arcuate film gate having an aperture therein, an exciter lamp located closely adjacent said film gate, a housing enclosing said exciter lamp, a photocell adjacent to said aperture and opposite to said exciter lamp, and a housing enclosing said photocell and having an aperture therein facing the film gate aperture whereby said sound reproducer and said control track reproducer each operates without interference from the other.

35 40 45 50 55 60 6. In combination with a photoelectric pickup device for reproducing records from film, an exciter lamp housing adapted to be mounted in a horizontal position for directing light through the film onto a photocell, said housing including a tubular member having an aperture in one side thereof for transmitting light from the exciter lamp and circumferential cooling fins extending from said housing on the sides away from said aperture.

JOSEPH LEMON UNDERHILL.
